CLAUDE E. FURGASON, OF LANSING, MICHIGAN, ASSIGNOR TO REO MOTOR CAR COMPANY, OF LANSING, MICHIGAN, A CORPORATION OF MICHIGAN.

SPARK-CONTROL MECHANISM.

Application filed March 23, 1926. Serial No. 96,904.

This invention relates to spark control mechanism and more particularly to mechanism of this character finding particular utility in connection with internal combustion engines used on motor vehicles and the like.

Because of the skill necessary to the proper manual control of the spark and the relative inadequacy of such control, automatic control of the spark for advancing and retarding the same consistent with the speed of the motor has become widely adopted in practice. However, where automatic spark control is provided, adequate provision must be made for the proper and complete control of the spark under all conditions inasmuch as the control thereof has been removed from the will of the operator.

A notable instance of the failure of some automatic spark controls resides in the improper control of the spark between the period of starting and the period at which the motor attains a speed sufficient to properly operate the control mechanism for advancing the spark. This deficiency is particularly noticeable in governor controlled spark advancing mechanism wherein the spark advance is accomplished by a governor mechanism the operation of which is in turn dependent upon the speed of the motor. This disadvantage of governor controlled spark advancing mechanisms has been remedied and the mechanism accordingly rendered more efficient by the provision of means such as illustrated in my prior application Serial Number 82,160 filed Jan. 18, 1926 wherein means is provided for positively initially advancing the spark to a point consistent with or in advance of the speed of the motor at starting and for holding the spark thus advanced until the automatic governor controlled mechanism asserts itself. This means for positively initially advancing the spark is operated in dependence upon and as a result of the actuation of the accelerator of the motor vehicle. As previously mentioned, automatic spark control mechanism must be adequate at all speeds of the motor and must contemplate all conditions such as starting and running under both heavy and light loads. To this end an efficient automatic spark control must provide positive means for controlling the spark aside and apart from the automatic or constant control which is dependent upon the

speed of the motor and which in the present instance consists of a governor controlled mechanism.

As an example, the governor control, in order to attain the highest degree of efficiency, must be so set as to cause as high an advance of the spark as is practical when the motor is idling or when the motor is under a light load. Starting at this point it necessarily follows that efficient operation demands that means be provided for automatically retarding the spark in proportion to the quantity of gas used as the load increases and conversely to advance the spark as the load decreases, at all speeds of the motor. Such automatic control in the present instance is operated directly in dependence upon the operation of the accelerator which as previously pointed out, also has operable consistent therewith means for positively advancing the spark prior to the moment at which the governor control exerts its influence.

As previously mentioned, it has been found that the greatest efficiency is obtained when the governor control is set so as to cause as high an advance of the spark as is practical when the motor is idling or under light load. Should the motor thereafter be abruptly placed under a heavy load as, for instance, when the vehicle starts up a grade, the accelerator must be depressed to furnish additional gas to compensate for this increased load. The advanced position of the spark under such conditions is too great for the amount of gas being fed to the motor and consequently under such conditions the motor is heard to "ping" or "knock" which is, at least, undesirable and frequently harmful to the motor.

To automatically compensate for this objection, the present invention contemplates the provision of means for positively retarding the spark in proportion to the quantity of gas used so as to automatically initially readjust the degree of advance of the spark with reference to the quantity of gas fed to the motor. As the quantity of gas used is dependent upon the extent of depression of the accelerator so this automatic spark retarding may conveniently be operated through the medium of the accelerator means. In operation, if the accelerator pedal is, for instance, fully depressed, a large quantity of gas will be fed to the motor to

compensate for the abrupt increase in load. The automatic spark control has, of course, previously taken the control of the spark from the operator as the governor has advanced the spark consistent with the speed of the motor. However, according to this invention, compensation for the increased supply of gas to the motor is rendered possible by a retarding of the spark operated simultaneously with and in dependence upon the depression of the accelerator pedal. As the motor adjusts itself under the increased load and increases its speed, the accelerator pedal will, as a consequence, be let up to reduce the supply of gas whereupon the means which previously effected the retarding of the spark, works conversely to effect an advance of the spark.

As a consequence of the above it will be apparent that the primary object of the present invention is to provide automatic means for positively controlling the spark under all conditions and speeds of the motor, aside from the automatic speed control means and in direct relation to the state of the load, and to this end consists in the novel details of construction and arrangements of parts which will be made more apparent as this description proceeds, especially when considered in connection with the accompanying drawings wherein;

Figure 1 is a side elevation of the mechanism forming the subject matter of the present invention.

Figure 2 is a top plan view of the structure illustrated in Figure 1 partly in section.

Figure 3 is a horizontal sectional view partly in section and partly in elevation.

Figure 4 is a sectional view taken substantially on the plane indicated on the line 4-4 of Figure 3 and

Figure 5 is a sectional view taken substantially on the plane indicated by the line 5-5 of Figure 3.

Referring now particularly to the drawings wherein like reference characters indicate like parts, it will be noted that there is illustrated fragmentarily the end of a generator shaft 10 which, through the medium of a spiral drive gear 11 meshing with a worm gear 12 drives the rotor shaft 13 which carries the arm 14 of the sparking mechanism. The spiral gear 11 is rotatably fixed upon the shaft 10 but longitudinally adjustable thereon which permits of changing the timing of the shaft 13 by such longitudinal adjustment of gear 11. While the shaft 10 is described as the generator shaft, it obviously may be any shaft driven in fixed relation to the speed of the motor.

As illustrated, the gear 11 is splined to the shaft 10 and is provided with a shank or sleeve portion 15 into which the end of shaft 10 extends. This sleeve 15 is pro-

vided with a pair of diametrically opposed slots 16 through which a pin 17 arranged transversely of the end of shaft 10 extends. A coil spring 18 is arranged between the end of shaft 10 and the closed end of sleeve 15 tending normally to urge the sleeve 15 to the right as shown in Figure 3.

Pivottally supported upon the pins 17 is a pair of weighted governor arms 19 provided with a pair of laterally extending cams 20 which are adapted to engage rollers 21 arranged diametrically on the sleeve 15 and mounted thereon by means of studs 22. As the governor is operated upon rotation of the shaft 10 it will swing about its pivot pins 17 to cause the cam surfaces 20 through the medium of their engagement with rollers 21 to move the spiral gear 11 in the direction of arrow A to thus advance the relative position of the rotor shaft 13 to that of shaft 10 thereby producing an advance of the spark.

As this advance of the spark is in consequence of the speed of the motor it becomes readily apparent that a proper advance of the spark will not be effected until the motor had attained a reasonable speed. Therefore in order to initially slightly advance the spark to facilitate the rapid increase in speed of the motor at the start, I have provided mechanism which includes a control shaft 23 rotatably mounted in an enlargement 24 of the shell or casing 25. One end of this shaft is formed with a head 26 provided with a cam face 27, adapted to engage the end of a push pin 28 which abuts at its other end the end of sleeve 15. To the other end of control shaft 23 is clamped a force lever 29 which is connected by means of a link 30 to the end of a rock lever 31 clamped upon the carburetor rocker shaft 32. The adjacent end of the motor crank case 33 is shown as being provided with a sleeve-like bearing for supporting the carburetor rocker shaft at this point. The reference character 34 indicates the accelerator pedal for actuating the usual throttle.

With the mechanism thus far described it will be apparent that upon a depression of the accelerator 34, lever 31 will be rocked and through the medium of link 30 on the force lever 29 control shaft 23 will be rocked to cause the cam 27 to engage push pin 28 displacing the same to move sleeve 15 and consequently gear 11 in the direction of arrow A thus causing a slight initial advance of the spark prior to the moment at which this control of the spark is assumed by the governor. This slight initial or partial advance to the spark is an advance of approximately between 12° and 15° . The total advance imparted to the spark by the governor is between 84° and 90° which represents the maximum advance limits for various types of motors.

Pin 28 has only a bearing engagement with sleeve 15 so that as soon as the engine has attained sufficient speed to cause the governor to assume control of the spark, then sleeve 15 is moved away out of contact with pin 28. Thus the cam 27 and pin 28 operated upon movement of the throttle function only initially and during the lower speed range of the engine while the governor functions during the higher speed range of the motor.

The reference character 35 indicates the shell of the distributor of the sparking mechanism which is supported upon a sleeve 36 which surrounds shaft 13 and may be rotatably supported in an extension 37 of the shell or housing 38. Projecting laterally from the sleeve 36 is a stud 39 provided with a head 40 recessed for the reception of the adjacent end of a push rod 41. The stud 39 projects through a circumferentially extending slot 42 formed in the extension 37 of the shell 38 so as to permit a rocking of the sleeve 36 and an oscillation of the pin 39. A shell-like abutment 43 is provided with which a spring 44 engages, the other end of which reposes in a recess in the end of the head 40. This spring normally urges a rotation of sleeve 36 in the direction of arrow B and consequently a rotation of shell 35 in a similar direction which operates to effect a retarding of the spark.

The end 45 of push rod 41 passes through an opening in the enlargement 24 of shell 35 for engagement with a cam surface 46 formed on the control shaft 23 adjacent the shaft end 45. In the normal position of the parts such as illustrated in Figures 3 and 4 the end 45 of rod 41 engages against the true circumference of shaft 23 so that sleeve 36 and consequently shell 35 are prevented from rotating in the direction of the arrow B as urged by the spring 44. However, as the throttle is operated to feed more gas to the motor and in consequence thereof shaft 23 is rocked in the direction of arrow C and cam surface 46 is brought opposite the end 45 of the push rod 41 thus permitting an endwise movement of this rod and the consequent rotation of sleeve 36 in the direction of arrow B. The extent of this rotation is dependent upon the amount of rocking of the shaft 23 which in turn depends upon the extent to which the accelerator pedal 34 has been depressed. As a consequence the degree to which the spark is retarded by this mechanism is in direct proportion to the amount of gas fed to the motor.

In operation, the herein described structure compensates for the differences between heavy and light loads by properly adjusting the spark in accordance therewith. By this apparatus the spark is advanced with a light load and retarded with a heavy load

with the intermediate positions of the spark depending upon the differences between light and heavy loads. The present device affords means for further controlling the spark after the governor controlled means has removed the control of the spark from the will of the operator. It will furthermore be noted that the control means herein are all purely mechanical and consequently the control may be positively effected. By operating the spark control in direct dependence upon the operation of the throttle or accelerator the spark control is made to respond directly to the variances of the load upon the motor as the accelerator is operated to compensate for such changes in load.

Obviously the invention is capable of various other uses and other forms of application than that disclosed in the present instance and furthermore various changes may be resorted to in many of the essential and all of the non-essential details as well as the arrangement of the parts without departing from the spirit and scope of this invention and to this end reservation is made to make such changes as may come within the purview of the accompanying claims.

What I claim as my invention is:

1. The combination with a throttle controlled internal combustion engine, an automatic speed controlled spark adjusting mechanism and means for initially slightly advancing said spark, of a constant control means for said spark, independent of said automatic mechanism and initial control means operable in dependence upon the adjustment of said throttle.

2. The combination with a throttle controlled internal combustion engine, an automatic speed controlled spark adjusting mechanism and initial spark control means for slightly advancing the spark, and an accelerator for actuating said throttle, of a constant control means for said spark and means actuated by said accelerator for operating said constant control means.

3. In an internal combustion engine, a throttle, a spark timing mechanism, an engine operated governor for automatically adjusting said timing mechanism in accordance with the speed of the engine, and means operated upon movement of said throttle for imparting two additional corrective adjustments to said timing mechanism.

4. In an internal combustion engine, an accelerator controlling a throttle, a spark timing mechanism, an engine operated governor for automatically adjusting said timing mechanism in accordance with the speed of the engine, and means operated by said accelerator for imparting two additional opposed adjustments to said timing mechanism.

5. In an internal combustion engine, an

accelerator controlling a throttle, a spark timing mechanism, an engine operated governor for automatically adjusting said timing mechanism in accordance with the speed of the engine, and means operated by said accelerator for initially slightly advancing said spark and for additionally adjusting said spark.

6. In an internal combustion engine, an accelerator controlling a throttle, a spark timing mechanism, an engine operated governor for automatically adjusting said timing mechanism in accordance with the speed of the engine, and means operated by said accelerator for initially slightly advancing said spark and for continuously additionally controlling said spark.

7. The combination with a throttle controlled internal combustion engine and a spark timing mechanism therefor, including two relatively movable parts, of an engine operated governor for automatically adjusting one of said timing mechanism parts in accordance with the speed of the engine, means connected to and operated upon a movement of said throttle for adjusting the other timing mechanism part and other means operable upon by said said throttle for initially slightly advancing the part of said timing mechanism controlled by said governor.

8. The combination with a throttle controlled internal combustion engine and a spark timing mechanism therefor, including two relatively movable parts, of an engine operated governor for automatically adjusting one of said timing mechanism parts in accordance with the speed of the engine, means operated by a movement of said throttle for adjusting the other timing mechanism part and other means operable upon movement of said throttle for initially slightly advancing one of said timing mechanism parts.

45 9. The combination with a throttle controlled internal combustion engine and a spark timing mechanism therefor, of an engine operated governor for automatically controlling said timing mechanism through the higher speed range of said engine, means operated upon the opening of said throttle for controlling said timing mechanism through the lower speed range of said engine and other means operated in dependence upon a movement of said throttle for constantly additionally adjusting said timing mechanism.

10. The combination with a throttle controlled internal combustion engine, of a spark timing mechanism including relatively movable parts, an engine operated governor for automatically adjusting one of said parts in accordance with the speed of the engine, means operated upon movement of the throttle for additionally adjusting the said timing mechanism part.

ing mechanism part and other means operated upon movement of said throttle for adjusting the other timing mechanism part.

11. The combination with a throttle controlled internal combustion engine, of a spark timing mechanism including relatively movable parts, an engine operated governor for automatically adjusting one of said parts in accordance with the speed of the engine, means operable upon movement of said throttle for adjusting said timing mechanism part to initially slightly advance said timing mechanism and other means operated upon movement of the said throttle for adjusting the other part of said timing mechanism.

12. In an internal combustion engine, a throttle, a spark timing mechanism including two relatively movable parts, an engine operated governor for automatically adjusting one of said timing mechanism parts in accordance with the speed of the engine, a shaft operable upon movement of said throttle, means operable by said shaft for initially advancing the timing mechanism part controlled by said governor and other means operable by said shaft for adjusting the other timing mechanism part.

13. In an internal combustion engine, a throttle, a spark timing mechanism including two relatively movable parts, an engine operated governor for automatically adjusting one of said timing mechanism parts in accordance with the speed of the engine, a shaft operable upon movement of said throttle, means operable by said shaft for initially slightly advancing one of said timing mechanism parts and other means operable by said shaft for adjusting the other timing mechanism part.

14. In an internal combustion engine, a throttle, a spark timing mechanism including two relatively movable parts, an engine operated governor for automatically adjusting one of said timing mechanism parts in accordance with the speed of the engine, a shaft operable upon movement of said throttle, cam means operable by said shaft for initially advancing the timing mechanism part controlled by said governor and other cam means operable by said shaft for adjusting the other timing mechanism part.

15. In an internal combustion engine, a throttle, a spark timing mechanism including two relatively movable parts, an engine operated governor for automatically adjusting one of said timing mechanism parts in accordance with the speed of the engine, a shaft actuated by a movement of said throttle, means operable by said shaft for controlling one of said timing mechanism parts during the lower speed range of the engine and other means operated by said shaft for adjusting the other timing mechanism part.

16. In an internal combustion engine, a throttle, a spark timing mechanism including two relatively movable parts, an engine operated governor for automatically adjusting one of said timing mechanism parts in accordance with the speed of the engine, a shaft actuated by a movement of said throttle, a member adjustable by said shaft and abutting the timing mechanism part 5 adjusted by said governor for controlling the same during the lower speed range of the engine and other means operated by said shaft for adjusting the other timing mechanism part.
17. The combination with an internal combustion engine, a throttle therefor and a spark timing mechanism including two relatively movable parts, of an engine operated governor for automatically adjusting one of 10 said timing mechanism parts in accordance with the speed of the engine, a shaft rotated upon actuation of said throttle, means operated by said shaft for imparting a limited additional adjustment to the timing mechanism part controlled by said governor and other means operated by said shaft provid- 15 ing a constant control for adjusting the other timing mechanism part.
18. The combination with an internal combustion engine spark timing mechanism and a throttle therefor, of cam means operated as said throttle is opened for initially advancing said timing mechanism and subsequently retarding said mechanism in proportion to the opening of said throttle. 20
19. The combination with a governor controlled spark timing mechanism, of cam means operated in dependence upon the position of the throttle for first advancing and then correcting the position of said timing mechanism in accordance to load conditions. 25
20. The combination with a spark timing mechanism for internal combustion engines and governor controlled means for controlling said spark in accordance with the speed of the engine, of cam means for initially additionally advancing said timing mechanism and subsequently partially retarding said mechanism in dependence upon increase 30 in the load.

In testimony whereof I affix my signature.
CLAUDE E. FURGASON.
